COAXIAL CABLE CONNECTOR

Heinz A. Blum, Hyattsville, and Juris E. Eksteins,
Takoma Park, Md., assignors to Entron, Inc., Bladensburg,
Md., a corporation of Delaware

Filed Sept. 8, 1961, Ser. No. 66,651

Term of patent 14 years

(Cl. D26—1)

FIG. 1.

FIG. 2.

FIG. 3.

FIG. 4

FIG. 1 is a perspective view of a coaxial cable connector showing our new design;

FIG. 2 is a side elevational view thereof, the side opposite thereto being substantially similar in appearance;

FIG. 3 is a bottom plan view thereof taken along the line of the protruding lower portion; and

FIG. 4 is a side elevation looking from the left in FIG. 2.

We claim:

The ornamental design for a coaxial cable connector, as shown and described.
